MANUFACTURE OF INSULATED ELECTRIC CONDUCTORS

Douglas Taft Hollingsworth, Knutsford, and James Alexander McCleery, Sale, England, assignors to W. T. Glover & Co. Limited, Manchester, England, a British company

Application October 29, 1951, Serial No. 253,686

Claims priority, application Great Britain November 14, 1950

3 Claims. (Cl. 154—2.25)

1

This invention relates to insulated electric conductors of the kind in which the conductor (or conductors) is enclosed in a metal tube and insulated from it by powder, for instance, magnesia or talc. The invention provides an improved manufacture carried out by a process in which the powder is fed into a tube around the conductor and compressed there.

In accordance with the invention the insulated conductor (or conductors) is manufactured by a continuous process in which the enclosing tube is formed by the gradual transverse bending of a strip of metal which is continuously moving forward, the bending bringing the edges together, after which they are united by welding or by soldering (soft or hard solder). In this continuous process the conductor (or conductors) also travels forward with the strip and becomes enclosed in the tube. As the bending of the strip proceeds the edges of the strip are brought closer and closer together and at an appropriate place in the path of the strip the powder is fed through the gap between the edges of the curved strip to a place in front of a reciprocating ram. From that region the powder is pushed forward into the closed part of the strip and consolidated thereby by the ram. The conductor (or conductors) passes through a hole in the ram. After the edges of the strip have been united to form a closed tube, the latter proceeds forward to a reducing die through which it is drawn, undergoing in the process a reduction of diameter and a further compression of the powder within it.

The invention will be described further with the aid of the accompanying drawings illustrating one form of construction by way of example and wherein

Figure 1 is a longitudinal view, partly in section, the figure being largely diagrammatic and not drawn to scale,

Figure 2 is a longitudinal view, partly in section, of a part of the apparatus shown in Figure 1 and drawn to an enlarged scale,

Figures 3, 4, 5 and 6 are sectional end elevations taken on the lines III—III, IV—IV, V—V, VI—VI respectively of Figure 2.

In the following description that end of the apparatus shown to the left of the figure is regarded as being the rear end and the opposite end, as the front end.

The apparatus comprises a reciprocating ram 1 working in a cylinder 2. The ram at its forward part is of reduced diameter and extends for some considerable distance beyond the end of its cylinder where it passes into a cylindrical passage 3

2

formed axially of a member 4. In its extreme forward position the front end of the ram 1 is disposed just inside the corresponding end of the member 4, as will be seen from the drawing.

The member 4, referred to hereinafter as the inner member, cooperates with an outer member 5 to form a shaping die for a metal strip of appropriate width which is fed in a continuous manner through the apparatus. The outer member of that die is relatively short as compared with the inner member and between the two members is an appropriately shaped passage 6 which extends forwards in a direction towards the longitudinal axis of the apparatus and tapers in width in that direction. The inner member 4 has a rear portion 7 having a wall thickness which is gradually reduced in the forward direction, an intermediate portion 8 of uniform wall thickness and a front portion 9, which gradually tapers in thickness and then continues as a cylindrical portion of uniform wall thickness.

The cylindrical intermediate part 8 of the inner member 4 is surrounded by and spaced from an outer cylindrical casing 10, the upper part of which has an aperture 11 through which insulating powder for a conductor 12 can be fed intermittently and in appropriate quantities through a feed hopper 13. Immediately in front of the casing 10 which cooperates with the intermediate cylindrical part 8 of the inner member 4 to form an elongated cylindrical die, is a member 14 which cooperates with the adjacent surface of the front portion 9 of the inner member 4 to provide a forming die which serves to bring together in abutting relationship the two edges of a strip passing through the machine.

The forward end of the passage 6 is in communication with the passage provided between the intermediate portion 8 and the casing 10 and the latter, at its front end communicates with the passage provided between the member 14 and the front portion 9 of the inner member 4.

Immediately in front of the member 14 is a device 15 which solders or otherwise joins together the abutting edges of the strip to form a complete tube, the diameter of which is reduced by drawing the tube through a die 16 by any suitable means.

The ram 1 has an axially disposed passage 18 through which the conductor 12, drawn off from a bobbin 19, passes in a continuous manner, entering the passage at the rear end of the ram. The conductor passes over a guide roller 20 and then passes in a straight line through the ram 1. The metal strip which is formed continuously

into a tube and which encloses the conductor insulated with powder fed in through the hopper 13, is shown at 21, 22 being a supply bobbin from which the flat strip is drawn off, through a tension control device 23 and around a guide roller 24. From the latter, the strip 21 passes through a preforming device 25 (see particularly Figure 3) into the front end of the passage 6. The device 25 has a transversely extending slot 34 through which the strip 21 passes, the slot commencing the shaping of the strip by bending it transversely to its length to facilitate its entry into the passage 6 where the main part of the transverse bending of the strip is effected and the edges of the strip caused to move towards each other and to provide between those edges a gap which gradually decreases in width in a direction towards the front end of the apparatus. After passing through the device 25, the strip passes from below the rear end of the cylinder 2 into the rear end of the passage 6.

During the passage of the strip through the casing 10, a small quantity of powder is discharged from the feed hopper 13, to the front or working end of the ram 1 which is then positioned (see Figure 2) a short distance to the rear of a port 26 in the intermediate part 8 of the inner member 4. The powder falls from the feed hopper through the aperture 11 in the casing 10, through the gap between the edges of the shaped strip (see Figure 5) and through the port 26 into the intermediate part 8. As the ram advances on its working stroke it closes the port 26, and pushes the powder in front of it, the ram continuing to move in the same direction until it enters that part of the tube where the edges of the tube have been joined together by the device 15 which completes the formation of the tube by soldering or otherwise joining the edges together. The ram moves with clearance in this part of the tube and presses the powder around the axially disposed conductor and also consolidates the latter. The completed tube 29 and enclosed insulated conductor then pass together through the drawing down die 16 which further compresses the powder insulation. An appropriate form of pulling device indicated by 17 may be used for pulling the insulated conductor with its enclosing tube through the die 16.

The reciprocation of the ram 1 at an appropriate rate is effected by a double acting device 27 comprising a piston working in a cylinder, air under pressure being fed into the cylinder alternately to opposite sides of the piston. The collar 28 on the ram serves as an emergency stop.

The broken line 30 indicates the path of an edge of the strip 21 as the latter passes from the pre-shaping device 25 to the space between the member 14 and the front portion 9 of the inner member 4.

The ram 1 reciprocates in bearings 31 and at its front end, the inner member 4 is formed with a recess 32 which receives packing material 33 to avoid the risk of powder reaching the bearings.

What we claim as our invention is:

1. A method of manufacturing a conductor insulated with powder and enclosed in a metal tube, by a continuous process, comprising continuously advancing in the direction of its length a metal strip, subjecting the said strip, as it advances, to a transverse bending to effect relative movement

of approach of its longitudinal edges and to give to the strip a tubular shape with a gap between its longitudinal edges, continuously advancing a conductor in the direction of its length into the tubular shaped part of the strip, supplying insulating material in the form of powder through the gap between the longitudinal edges of the tubular part of the strip to the interior of that part, joining together the longitudinal edges of

5 the tubular part at a place in advance of that at which the supply of insulating powder takes place thereby forming a complete tube, pushing forward the powder in the tubular part to a place adjacent that at which the longitudinal edges 10 have been joined together and reducing the diameter of the complete tube, thereby compressing the powder therein.

2. An apparatus for the manufacture, as a continuous operation, of a powder-insulated conductor enclosed in a metal tube, comprising a shaping die which transversely bends a metal strip passing therethrough to form an incomplete tube having a gap between its longitudinal edges, a reciprocable ram working in a bore in the shaping die, a device for feeding a powder insulant through the gap in the incomplete tube to the interior of the latter in front of the reciprocable ram, means for closing the gap in the incomplete tube to form a complete tube, the said gap-closing means being mounted in advance of the powder-feeding device, a drawing-down die mounted in advance of the gap-closing means, and means for drawing the complete tube together with a wire and powder insulant therein 30 through the drawing-down die, reducing the diameter of the tube and compressing the powder therein.

3. An apparatus for the manufacture, as a continuous operation, of a powder-insulated conductor enclosed in a metal tube, comprising a shaping die comprising spaced inner and outer members having their adjacent surfaces shaped to bend a metal strip passing therebetween into tubular form with a gap between its longitudinal edges, thereby forming an incomplete tube, the inner member of the shaping die having a bore therein, a reciprocable ram working in the bore and having a longitudinally extending passage, a feed device for discharging powder through the gap in the incomplete tube in front of the ram, means for closing the said gap to form a complete tube, the ram having a working stroke which extends to a point adjacent the gap-closing means, a drawing-down die mounted in front 45 of the latter and means for drawing a metal strip through the shaping die and a wire through the passage in the ram and the completed tube together with the wire and powder insulant within the tube, through the drawing-down die to reduce the diameter of the tube and compress the powder.
